UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

MINING MACHINE

Application filed February 19, 1930, Serial No. 429,654. Renewed October 31, 1930.

This invention relates to improvements in mining machines and more particularly has reference to improved flexible feeding means for a coal mining machine of the continuous cutter, bottom cutting type.

An object of this invention is to provide an improved coal mining machine and more particularly improved feeding means for such a machine. Another object is to provide an improved mining machine of the flexibly fed, continuous cutter, bottom cutting type which is extremely low in height, especially adapted to use in "lowvein" work. A further object of this invention is to provide an improved mining machine of the flexibly fed room and pillar type. Another object of this invention is to provide an improved mining machine of the aforesaid character having improved feeding and guiding mechanism and more particularly improved feeding and guiding means for a room and pillar type of mining machine whereby the machine may be fed and controlled in a more facile and expeditious manner. A further object is to provide an improved mining machine of the room and pillar, "lowvein" type having improved feeding and guiding mechanism wherein separate relatively rotatable, power operated and controlled feed operating and controlling members respectively cooperating with separate flexible feeding elements are employed for feeding and guiding the machine for sliding movement over the mine bottom, the said members and the driving mechanism therefor being arranged in an improved manner on the machine whereby the machine is rendered extremely compact vertically. Another object is to provide a flexible feeding means of the aforesaid character improved driving and controlling means for the feed operating and controlling members whereby the latter may be separately or simultaneously driven in a direction to draw in their respective flexible feeding elements at relatively low speed or at relatively high speed and having incorporated therein improved control mechanism whereby the said members may rotate in a direction to pay out their re-

spective flexible feeding elements under various degrees of operator-controlled frictional resistance or without such resistance as conditions may require. A further object is to provide in such a feeding means improved mechanism including a fast and slow speed gear train for each member through which it, but not the other member, is driven and means for connecting each member to either of its gear trains whereby said members may be rotated independently in winding direction at either a relatively high speed or a relatively low speed, each gear train for each member having a separate friction controlling clutch whereby either member may be driven at either speed at will. These and other objects and advantages of this invention will, however, hereinafter more fully appear.

In the accompanying drawings there is shown for purposes of illustration one embodiment which the invention may assume in practice.

In these drawings,—

Fig. 1 is a plan view of the illustrative embodiment of the improved mining machine.

Fig. 2 is an enlarged fragmentary plan view of the feeding end of the machine shown in Fig. 1, the top cover plate being removed and parts shown in horizontal section to illustrate structural details.

Fig. 3 is a transverse vertical sectional view taken substantially on line 3-3 of Fig. 2.

Fig. 4 is a central longitudinally extending vertical sectional view taken substantially on line 4-4 of Fig. 2.

Fig. 5 is a detail sectional view illustrating the central bearing support for one of the winding drums.

Fig. 6 is a detail sectional view illustrating the resilient pivotal mounting for the clutch shippers.

In this illustrative embodiment of the invention the improved flexible feeding means is shown embodied in a coal mining machine of the continuous cutter, bottom cutting, room and pillar type although it will be evident that the various novel features of the

improved feeding means may be incorporated in mining machines of various other types without departing from the spirit of the invention. This mining machine generally comprises a low compact machine frame or body 1 of generally rectangular shape having a smooth plane bottom surface 2 upon which the machine is slidably supported for movement over the mine bottom. 8 As is usual in mining machines of the room and pillar type, rigidly secured within the machine frame and projecting forwardly lengthwise thereof is an elongated plane cutter bar 3 supporting on its margin an endless cutter bit carrying cutter chain 4. 10 Arranged at the rear end of the machine at opposite sides of the longitudinal median line thereof are relatively rotatable feed operating and controlling members 6 and 7 herein in the form of cable winding or haulage drums with which feeding and controlling cables 8 and 9 respectively cooperate. 15 As illustrated, carried by the machine frame is a centrally located motor 10, which may be of reversible electric type, of a low compact design having its power shaft 11 horizontally disposed and extending longitudinally of the machine. The cutter chain 4 is operatively connected to the front end of the motor shaft through any suitable transmission means, which may be of the same general character as that disclosed in a co-pending application to one Morris P. Holmes, Ser. No. 136,446, filed Sept. 20, 1926. 20 The feed operating and controlling drums 6 and 7 are disposed on parallel vertical axes in a novel manner and are operatively connected to the rear end of the motor shaft through improved transmission means to be hereinafter described. If desired, the feed cables may be extended directly from the feed drums during the feeding of the machine but in the present instance there are provided at the opposite rear corners of the machine frame on upstanding axes, guiding sheaves 12 and 13. A central guide sheave 14 is also provided while arranged at the opposite sides of the front end of the machine frame are guide sheaves 15 and 16. The feeding and controlling cables 8 and 9, 25 after passing around any preferred guide sheaves, may be extended in any preferred direction from the machine and attached to suitably positioned anchors in the manner which is well understood in the mining machine art.

Now referring to the improved feeding mechanism and more particularly to the improved transmission means between the motor and the feed and controlling drums, it will be noted that secured to the rear end of the motor shaft 11 is a spur pinion 17 meshing with spur gears 18 and 19 journaled on horizontal stub shafts 20 fixed 30 within the machine frame and arranged

parallel with the motor shaft. These spur gears 18, 19 mesh with an internal gear 21 keyed, as shown in Fig. 4, to a horizontal longitudinally extending shaft 22 suitably journaled within the machine frame. The axis of this shaft lies in a longitudinally extending vertical plane including the motor axis. Fixed to the shaft 22 is a spur gear 23 meshing with a spur gear 24 keyed to a horizontal shaft 25 arranged parallel with, and directly above, the shaft 22 and likewise suitably journaled within the machine frame. In the present instance the gears 23 and 24 are change speed gears and may be removed and replaced with gears having a different tooth ratio so that differently related predetermined feeding speeds may be obtained. Herein, keyed to the shafts 22 and 25 respectively are worms 26 and 27, the worm 26 having teeth of steeper lead and oppositely inclined from the teeth of the worm 27. However, since the shafts 22 and 25 rotate in opposite directions the worms effect drive in the same direction although at different speeds. A fast and slow predetermined speed transmission mechanism is provided between the worms 26, 27 and each of the winding drums and as the structure of each of these transmission mechanisms is substantially identical the description of one will suffice for both. Now referring to the fast and slow predetermined speed driving mechanism between the worms and the winding drum 6, it will be observed that meshing with the worm 26 is a fast speed worm wheel 28 while meshing with the worm 27 is a slow speed worm wheel 29, these worm wheels being coaxially arranged on a vertically extending axis parallel with the drum axis. These worm wheels are suitably journaled within the machine frame and are arranged in an extremely compact manner thereby reducing the vertical dimension of the feeding mechanism so that the height of the machine is determined by the vertical dimension of the motor 10. Journaled within bearings supported by the hubs of the worm wheels 28, 29 is a vertical shaft 30 and the worm wheels are selectively connectable to the shaft by means of multiple disc clutches 31 and 32 respectively. Keyed to the lower end of the vertical shaft 30 is a spur pinion 33 meshing with the teeth of an internal gear 34 herein formed integrally with the winding drum. It will thus be seen that when friction clutch 31 is applied and clutch 32 released, the winding drum 6 may be driven in winding direction at a relatively high speed through gearing 17, 18, 19, 21, shaft 22, worm gearing 26, 28, shaft 30, and the spur pinion 33 meshing with the internal gear 34 secured to the drum. It will also be seen that when clutch 31 is released and clutch 32 applied the winding drum 6 may 35 40 45 50 55 60 65 70 75 80 85 90 95 100 105 110 115 120

be driven in winding direction at a relatively slow speed through the reduction gearing 23, 24 and worm gearing 27, 29. As previously mentioned the transmission mechanism for the winding drum 7 is substantially identical to that for the winding drum 6 and includes fast and slow speed worm wheels 35 and 36 meshing with the worms 26 and 27 respectively and connectible by similar multiple disc clutches 37 and 38 in driving relation with the winding drum 7. When one or the other of the friction clutches 37, 38 is applied and the other released the winding drum 7 may be rotated in winding direction at either a relatively high speed or a relatively low speed, depending upon which one of the clutches is applied. It will be noted that the drums may rotate separately or simultaneously and that the friction clutches may be so released as to permit the drums to rotate in unwinding direction under various degrees of frictional resistance. Upon full release of the clutches the drums may rotate freely. If desired, a usual main feed drum controlling clutch may be interposed in the drive between the vertical shaft 30 and the drum or in any other suitable location so that at certain times the drums may be entirely disconnected from their drive, for instance when it is desired to unwind the feed cables from the drums by hand. Such clutches are usual in mining machines of the type disclosed and as they do not specifically enter into this invention illustration of the same is thought to be unnecessary.

The operating means for the friction clutches 31 and 32 within the worm wheels 28, 29 respectively herein comprises a shipper yoke 40 pivoted at 41 on the machine frame and equipped with rollers 42 engageable with the opposed plane surfaces of cylindrical pressure plates 43 and 44 for the clutches respectively. Each of these plates has projections extending into engagement with the adjacent end disc of the clutch. The arm 45 of the shipper yoke is bifurcated at 46 and straddles a vertical bolt 47 threadedly connected at 48 within the machine frame. The bifurcated portion of the shipper yoke engages transverse plates yieldably connected together and forming a resilient pivotal mounting for the shipper yoke. Upon overload of either of the clutches this pivotal mounting is adapted to yield, permitting the clutch to slip and eliminating the possibility of breakage of the feed driving parts. The means for swinging the shipper yoke about its pivot comprises a shaft 49 rotatably mounted within suitable bearings carried by the machine frame and having an eccentric portion 50 pivotally connected to the shipper yoke. Secured to the outer end of the shaft 49 is an operating handle 51 conveniently located at the rear

end of the machine. It will be thus seen that when the handle 51 is rotated in one direction or the other the shipper yoke 40 is swung upwardly or downwardly about its pivot to apply either the clutch 31 or the clutch 32. The parts are so arranged that it is impossible to effect simultaneous application of the clutches, one clutch always being released when the other is applied. Similar operating mechanism including a pivoted shipper yoke 52, operating shaft 53 and operating handle 54 is employed for controlling the friction clutches 37 and 38 of the drive for the winding drum 7.

Each of the drums 6 and 7 is journaled upon the machine frame in a similar manner and, as shown in Fig. 5, the winding drum 6 is provided with a hub portion 55 rotatably supported on ball bearings 56 within the machine frame. A spacing sleeve 57 and a central holding bolt 58 are provided for maintaining the drum bearings in proper spaced relation. As shown in Fig. 3, the drums 6 and 7 are arranged within a chamber 59 extending transversely completely across the lower portion of the machine frame so that the feed cables may be extended from the machine in various directions.

The mining machine is adapted to be supported on a self-propelled transport truck during movement thereof about the mine and mechanism is provided on the machine for driving the truck wheels. This truck driving mechanism includes an extension 60 on the shaft 22 having keyed thereto on its reduced end a cylindrical truck driving member 61 journaled within a bore 62 formed within the machine frame. This member 61 is provided with a central polygonal socket 63 which is adapted to receive a similarly shaped member on the truck. When the machine is mounted on the truck with the member 61 in driving relation with the truck member, the truck wheels may be driven from the motor 10 through gears 17, 18, 19, 21, shaft 22, shaft extension 60 and the truck driving member 61 on the machine. Various modes of operation of the improved machine will be clearly apparent to those skilled in the art and as the method of use of a room and pillar mining machine is well known further description of the operation of the machine is thought unnecessary.

As a result of this improved construction it will be observed that an extremely low, comparatively short, compact machine is produced and one which is accordingly adapted to use in even the lowest commercially workable veins of coal. Furthermore this improved construction enables an extremely compact machine to be obtained wherein the length thereof is reduced to a minimum, the improved feed mechanism and the novel compact arrangement of the driv-

ing gears and feed drums on the machine reducing the dimensions of the machine to a minimum. Furthermore by arranging the feed and controlling drums in the novel 5 manner disclosed and by providing the improved arrangement of the transmission mechanism for driving the drums the machine is not only rendered extremely compact, but is also exceedingly flexible in operation and easy to handle especially during the various maneuvering of the machine to 10 position the same to effect its sumping, transverse, and withdrawal cuts in accordance with the room and pillar system of mining. 15 It will also be noted that the improved feeding mechanism is extremely well balanced and symmetrical in design, the driving mechanisms for the drums being substantially identical in construction, thereby reducing the number of different parts with 20 the resultant decrease in the cost of manufacture and replacement. These and other uses and advantages of the improved mining machine will be clearly apparent to those 25 skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure 35 by Letters Patent is:

1. A mining machine feeding mechanism including relatively rotatable feeding members each disposed on a vertical axis and adapted to cooperate directly with flexible 40 feeding means, and motor operated driving means for said members including a plural predetermined speed transmission mechanism for each member through which it, but not the other member, is driven, each transmission mechanism including a fast predetermined speed gear train and a slow predetermined speed gear train and a friction controlling clutch for each train for connecting said trains in driving relation with their respective members.

2. A mining machine feeding mechanism including relatively rotatable feeding members each disposed on a vertical axis and adapted to cooperate directly with flexible 45 feeding means, and motor operated driving means for said members including a plural predetermined speed transmission mechanism for each member through which it, but not the other member, is driven for rotating said members in a direction to draw in their respective feeding means either separately or simultaneously, each transmission mechanism including a fast predetermined speed gear train and a slow predetermined speed 50 gear train and a friction controlling clutch

for each train for connecting said trains in driving relation with their respective members.

3. A mining machine feeding mechanism including relatively rotatable feeding members each disposed on a vertical axis and adapted to cooperate directly with flexible feeding means, and motor operated driving means for said members including a plural predetermined speed transmission mechanism for each member through which it, but not the other member, is driven for rotating said members either separately or simultaneously in a direction to draw in their respective feeding means, each transmission mechanism including a fast predetermined speed gear train and a slow predetermined speed gear train and a friction controlling clutch for each train for connecting said trains in driving relation with their respective members and for permitting said members to rotate in a direction to pay out their respective flexible feeding means under various degrees of frictional resistance.

4. A mining machine feeding mechanism including relatively rotatable feeding members each disposed on a vertical axis and adapted to cooperate directly with flexible feeding means, and motor operated driving means for said members including a plural predetermined speed transmission mechanism for each member through which it, but not the other member, is driven for rotating said members either separately or simultaneously in a direction to draw in their respective feeding means, each transmission mechanism including a fast predetermined speed gear train and a slow predetermined speed gear train and a friction controlling clutch for each train for connecting said trains in driving relation with their respective members, for permitting said members to rotate in a direction to pay out their respective flexible feeding means under various degrees of frictional resistance, or without such resistance.

5. A mining machine feeding mechanism including relatively rotatable feeding members each disposed on a vertical axis and adapted to cooperate directly with flexible feeding means, and motor operated driving means for said members including a plural predetermined speed transmission mechanism for each member through which it, but not the other member, is driven, said transmission mechanisms each including separate fast and slow predetermined speed worm gear trains, one gear train being inoperative to drive its respective member while the other gear train is connected in driving relation with its member.

6. A mining machine feeding mechanism including relatively rotatable feeding members each disposed on a vertical axis and adapted to cooperate directly with flexible

- feeding means, and motor operated driving means for said members including a plural predetermined speed transmission mechanism for each member through which it, but 5 not the other member, is driven, said transmission mechanisms each including separate fast and slow predetermined speed gear trains, one gear train being inoperative to drive its respective member while the other 10 gear train is connected in driving relation with its member and selectively operable clutches for alternatively connecting said gear trains in driving relation with their respective members.
- 15 7. A mining machine feeding mechanism including relatively rotatable feeding members each adapted to cooperate directly with flexible feeding means, and motor operated driving means for said members including 20 a fast and slow predetermined speed gear train for each member through which it, but not the other member, is driven, all of the gears of said gear trains rotating on fixed axes during drive at either speed and the 25 final gears of said trains being arranged on vertical axes.
8. A mining machine feeding mechanism including relatively rotatable feeding members disposed on vertical axes and each 30 adapted to cooperate directly with flexible feeding means, and motor operated driving means for said members including a fast and slow predetermined speed gear train for each member through which it, but not the 35 other feeding member, is driven, all of the gears of said gear trains rotating on fixed axes during drive at either speed and the final gears of said trains being arranged on axes parallel to a line parallel with the axes 40 of said feeding members.
9. A mining machine feeding mechanism including relatively rotatable feeding members rotating on vertical axes and each adapted to cooperate directly with flexible 45 feeding means, and motor operated driving means for said members including fast and slow predetermined speed gear trains for each member through which it, but not the other member, is driven and control clutches 50 for each train for rotating said members in a direction to draw in their respective flexible feeding means at a relatively fast or a relatively slow speed.
10. A mining machine feeding mechanism 55 including relatively rotatable feeding members rotating on vertical axes and each adapted to cooperate directly with flexible feeding means, and motor operated driving means for said members including fast and slow predetermined speed gear trains for each member through which it, but not the other member, is driven and control clutches for each train for rotating said members in a direction to draw in their respective flexible feeding means at a relatively fast 60 or a relatively slow speed, or to permit said members to rotate in a direction to pay out their respective feeding means under various degrees of frictional resistance.
11. A mining machine feeding mechanism 70 including relatively rotatable feeding members rotating on vertical axes and each adapted to cooperate directly with flexible feeding means, and motor operated driving means for said members including fast and slow predetermined speed gear trains for each member through which it, but not the other member, is driven and control clutches for each train for rotating said members in a direction to draw in their respective flexible feeding means at a relatively fast or a relatively slow speed, to permit said members to rotate in a direction to pay out their respective feeding means under various degrees of frictional resistance or without such resistance.
12. A mining machine feeding mechanism 80 including relatively rotatable feeding members each adapted to cooperate directly with flexible feeding means and disposed on vertical axes, and motor operated driving means for said members including a fast and slow predetermined speed transmission mechanism for each member through which it, but not the other member, is driven, all 85 of the gears of said transmission mechanisms rotating on fixed axes during drive at either speed.
13. A mining machine feeding mechanism 90 including relatively rotatable feeding members each adapted to cooperate directly with flexible feeding means and disposed on vertical axes, and motor operated driving means for said members including a fast and slow predetermined speed transmission mechanism for each member through which it, but not the other member, is driven, all 95 of the gears of said transmission mechanisms rotating on fixed axes during drive at either speed.
14. A mining machine feeding mechanism 100 including relatively rotatable feeding members each adapted to cooperate directly with flexible feeding means and disposed on vertical axes, and motor operated driving means for said members including a fast and slow predetermined speed transmission mechanism for each member through which it, but not the other member, is driven, all 105 of the gears of said transmission mechanisms rotating on fixed axes during drive at either speed and each transmission mechanism including a fast predetermined speed gear train and a slow predetermined speed gear train.
15. A mining machine feeding mechanism 110 including relatively rotatable feeding members each adapted to cooperate directly with flexible feeding means and disposed on vertical axes, and motor operated driving means for said members including a fast and slow predetermined speed transmission mechanism for each member through which it, but not the other member, is driven, all 115 of the gears of said transmission mechanisms rotating on fixed axes during drive at either speed and each transmission mechanism including a fast predetermined speed gear train and a slow predetermined speed gear train and controlling clutches, one individual to each gear train for alternatively con- 120
16. A mining machine feeding mechanism 125 including relatively rotatable feeding members each adapted to cooperate directly with flexible feeding means and disposed on vertical axes, and motor operated driving means for said members including a fast and slow predetermined speed transmission mechanism for each member through which it, but not the other member, is driven, all 130 of the gears of said transmission mechanisms rotating on fixed axes during drive at either speed and each transmission mechanism including a fast predetermined speed gear train and a slow predetermined speed gear train and controlling clutches, one individual to each gear train for alternatively con-

necting said gear trains in driving relation with their respective members.

15. A mining machine feeding mechanism including relatively rotatable feeding members each adapted to cooperate directly with flexible feeding means, and motor operated driving means therefore including a fast and slow predetermined speed transmission mechanism for each member through which it, but not the other member, is driven, each transmission mechanism including a fast predetermined speed gear train and a slow predetermined speed gear train and each gear train having a final gear individual thereto and rotatable about a vertical axis at the respective predetermined speed of the train.

16. A mining machine feeding mechanism including relatively rotatable feeding members each adapted to cooperate directly with flexible feeding means, and motor operated driving means therefor including a fast and slow predetermined speed transmission mechanism for each member through which it, but not the other member, is driven, each transmission mechanism including a fast predetermined speed gear train and a slow predetermined speed gear train and each gear train having a final gear individual thereto and rotatable about a vertical axis at the respective predetermined terminal speed of the train and friction controlling clutches, one individual to each terminal gear, for selectively connecting said terminal gears in driving relation with their respective members.

17. A mining machine feeding mechanism including relatively rotatable feeding members each adapted to cooperate directly with flexible feeding means, and motor operated driving means therefor including a fast and slow predetermined speed transmission mechanism for each member through which it, but not the other member, is driven, each transmission mechanism including a fast predetermined gear train and a slow predetermined gear train, the gear trains for each member including final gears respectively individual thereto and rotatable about a vertical axis at the respective predetermined speeds of the trains and in coaxial relation.

18. A mining machine feeding mechanism including relatively rotatable feeding members each adapted to cooperate directly with flexible feeding means, and motor operated driving means therefor including a fast and slow predetermined speed transmission mechanism for each member through which it, but not the other member, is driven, each transmission mechanism including a fast predetermined speed gear train and a slow predetermined speed gear train, said gear trains including a fast speed worm and a slow speed worm and said fast and slow

speed worms rotating on parallel longitudinally extending axes and being so disposed that a vertical plane to which their axes are perpendicular cuts both of said worms.

19. A mining machine feeding mechanism including relatively rotatable feeding members each adapted to cooperate directly with flexible feeding means, and motor operated driving means therefor including a fast and slow predetermined speed transmission mechanism for each member through which it, but not the other member, is driven, each transmission mechanism including a fast predetermined speed gear train and a slow predetermined speed gear train, said gear trains of each transmission mechanism including a fast speed worm and a slow speed worm, said worms rotating on parallel longitudinally extending axes, and worm wheels meshing with each worm, said worm wheels, in each of said fast and slow speed transmission mechanisms, being coaxial, and the axis of worm wheel rotation of said different fast and slow speed transmissions being parallel.

20. A mining machine feeding mechanism including relatively rotatable feeding members each adapted to cooperate directly with flexible feeding means, and motor operated driving means therefor including a fast and slow predetermined speed transmission mechanism for each member through which it, but not the other member, is driven, each transmission mechanism including a fast predetermined speed gear train and a slow predetermined speed gear train, said gear trains of each transmission mechanism including a fast speed worm and a slow speed worm, said worms rotating on parallel longitudinally extending axes, worm wheels meshing with each worm, said worm wheels, in each of said fast and slow speed transmission mechanisms, being coaxial, and the axes of worm wheel rotation of said different fast and slow speed transmissions being parallel, and controlling clutches for connecting said worm wheels in driving relation with their respective members.

21. A mining machine feeding mechanism including relatively rotatable feeding members each disposed on a vertical axis and adapted to cooperate directly with flexible feeding means, and motor operated driving means for said members including a plural predetermined speed transmission mechanism for each member through which it, but not the other member, is driven, each transmission mechanism including a fast predetermined speed gear train and a slow predetermined speed gear train, and clutch devices for selectively connecting either train in driving relation with their respective feeding member.

including relatively rotatable feeding members each disposed on a vertical axis and adapted to cooperate directly with flexible feeding means, and motor operated driving means for said members including a plural predetermined speed transmission mechanism for each member through which it, but not the other member, is driven, each transmission mechanism including a fast 5 predetermined speed gear train and a slow predetermined speed gear train, and a plurality of clutch devices, one individual to each gear train, for selectively connecting said trains in driving relation with their 10 respective feeding member.

23. A mining machine feeding mechanism including relatively rotatable feeding members each adapted to cooperate directly with flexible feeding means, and motor operated 20 driving means for said members including a plural predetermined speed transmission mechanism for each member through which it, but not the other member, is driven, said transmission mechanisms being arranged 25 generally on vertical axes and each including a fast predetermined speed gear train and a slow predetermined speed gear train, and clutch devices for selectively connecting said trains in driving relation with their 30 respective feeding members.

24. A mining machine feeding mechanism including relatively rotatable feeding members each adapted to cooperate directly with flexible feeding means, and motor operated 35 driving means for said members including a plural predetermined speed transmission mechanism for each member through which it, but not the other member, is driven, said transmission mechanisms being arranged 40 generally on vertical axes and each including a fast predetermined speed gear train and a slow predetermined speed gear train, and a plurality of clutch devices, one individual to each gear train, for selectively 45 connecting said trains in driving relation with their respective feeding members.

25. A mining machine feeding mechanism including relatively rotatable feeding members each adapted to cooperate directly with 50 flexible feeding means, and motor operated driving means for said members including a plural predetermined speed transmission mechanism for each member through which it, but not the other member, is driven, each 55 transmission mechanism including a fast predetermined speed gear train and a slow predetermined speed gear train and each gear train including a final gear individual thereto and rotating on a vertical axis at the 60 respective predetermined terminal speed of the train, and a plurality of clutches, one individual to each gear train, for selectively connecting said trains in driving relation with their respective feeding members.

65 26. A mining machine feeding mechanism

including relatively rotatable feeding members each disposed on a vertical axis and adapted to cooperate directly with flexible feeding means, and motor operated driving means for said members including a plural 70 predetermined speed transmission mechanism for each member, through which it, but not the other member, is driven, each transmission mechanism including fast and slow predetermined speed gear trains, all of the 75 gears of said gear trains rotating on fixed axes during drive at either speed.

27. A mining machine feeding mechanism including relatively rotatable feeding members each disposed on a vertical axis and adapted to cooperate directly with flexible feeding means, and motor operated driving means for said members including a fast and slow predetermined speed transmission 80 mechanism for each member through which it, but not the other member, is driven, each transmission mechanism including a fast predetermined speed worm gear train and a slow predetermined speed worm gear train, and clutches for selectively connecting said 85 trains in driving relation with their respective feeding members.

28. A mining machine feeding mechanism including relatively rotatable feeding members each adapted to cooperate directly with 90 flexible feeding means, and motor operated driving means for said members including a fast and slow predetermined speed transmission mechanism for each member through which it, but not the other member, is 95 driven, each transmission mechanism including a fast predetermined speed worm gear train and a slow predetermined speed worm gear train, each of said trains including a worm wheel individual thereto and rotating about a vertical axis, and clutches for selectively connecting said trains in driving relation with their respective feeding members.

29. A mining machine feeding mechanism including relatively rotatable feeding members each adapted to cooperate directly with 100 flexible feeding means, and motor operated driving means for said members including a fast and slow predetermined speed transmission mechanism for each member through 105 which it, but not the other member, is driven, each transmission mechanism including a fast predetermined speed worm gear train and a slow predetermined speed worm gear train, the trains for driving each of said feeding members including worm wheels rotating about vertical axes and worms rotating on parallel longitudinally extending axes and meshing with said worm 110 wheels respectively, and clutches for selectively connecting said trains in driving relation with their respective feeding members.

In testimony whereof I affix my signature.
CHARLES F. OSGOOD.
